RAILWAY MAIL CAR

Samuel E. Wiley, Nashville, Tenn.

Application January 14, 1936, Serial No. 59,148

9 Claims. (Cl. 105—1)

My invention relates generally to railway mail handling and transporting means, and particularly to a motorized railway mail car for picking up, handling, and discharging mail while traveling at unusually high speed, and without slowing up, and which avoids the destruction of mail bags and receptacles while traveling at such high speeds, and an important object of the invention is to provide a car of the character indicated which will enable the picking up, sorting, and delivery of mail independently of or in cooperation with the regular railway mail system, whereby the transportation and delivery of mail by land may be greatly facilitated and speeded up, so as to be capable of competing favorably with the air mail systems.

Another important object of the invention is to provide a car of the character indicated above which is suitable for use on the rails of the regular railway systems or for use on independent rails or tracks paralleling the regular railway system or taking short-cuts in the interest of speed and safety.

Another important object of the invention is to provide in a car of the character indicated above means for picking up the mail from a mailbag rack at a station or other place while the car is traveling at extraordinarily high speed, in such a way that the bag or bags are not subjected to the impact ordinarily given them by the usual pick-up devices while the train embodying the same is moving at a high rate of speed, the said means including arrangements whereby the bag or bags are picked up at a speed corresponding to the speed of the car and delivered to the interior of the car at gradually reduced rates of travel toward the rear of the car.

Another important object of the invention is to provide in a car of the character indicated above mechanically operated means for delivering or dropping from the car at a given station or other place, mailbags destined for delivery there at a speed of motion from the rear of the car substantially approaching the speed of forward motion of the car, so that the bags of mail are deposited on the tracks without such momentum as would cause heavy and damaging impact of the bags with the ground.

Other important objects of my invention will be apparent from a reading of the following description in connection with the drawings, wherein for purposes of illustration I have shown a preferred embodiment of my invention.

In the drawings:—

Figure 1 is a general longitudinal vertical sec-

tional view taken through the embodiment and showing the interior arrangements thereof.

Figure 2 is an elevational view of a portion of the rear or back of the car.

Figure 3 is a longitudinal vertical sectional view through the rear of the car showing the delivering gate open.

Figure 4 is a horizontal sectional view taken through Figure 1 approximately on the line 4—4 and looking downwardly.

Figure 5 is an enlarged transverse vertical sectional view taken through the clutch mechanism.

Figure 6 is a transverse vertical sectional view taken through Figure 1 approximately on the line 5—5 and looking toward the left.

Figure 7 is a horizontal sectional view taken through the rear of the car and showing the mailbag delivering or discharging platform in discharging position.

Figure 8 is a longitudinal vertical sectional view taken through Figure 4 approximately on the line 8—8 and looking upwardly in the direction of the arrows.

Figure 9 is a horizontal sectional view taken through Figure 1 approximately on the line 9—9 and looking downwardly and showing the mail discharging platform in inoperative retracted position with the tail gate in closed position.

Figure 10 is a longitudinal vertical sectional view taken through Figure 9 approximately on the line 10—10 and looking downwardly in the direction of the arrows.

Figure 11 is a perspective view of the mail delivery platform latch.

Referring in detail to the drawings, the numeral 5 generally designates the frame or chassis of the car which has a forward part 6 elevated over the forward truck 7 and a rear part 8 elevated over the rear truck 9, the remaining portion of the chassis being depressed to lower the center of gravity, give adequate ceiling height, and enable having the mail handling mechanism on a low level.

The streamlined body generally designated 10 is generally rectangular in cross section and has the floor 11 conforming to the chassis 5 and the generally parallel side walls 12 and 13 terminating in the rounded nose 14 which slants forwardly and downwardly as indicated in Figure 1 and 50 has the mail pick-up opening 15 closed by the curved sliding doors 16, and 17 in the upper part thereof, and in the lower part thereof the engineer's window 18.

Above and defining the engineer's compart-

55

ment and the mail handling compartments is the ceiling partition 19' which extends from the front of the car to the compartment 19 at the rear of the car and defines above it the conveyor compartment 20.

5 A transverse partition 21 intermediate the ends of the car define mail handling rooms and the engineer's compartment while a rearward partition 22 defines the front of the compartment 19.

10 The wind entering the opening 15 in the car if proceeding at a high speed travels through the conveyor compartment 20 and passes through the screened opening 52' in the end wall 51 of the compartment 20 and then the air passes into the

15 duct 23 which underlies the downwardly curved rear deck 25 of the car and overlies the compartment 19. The air or wind is then broken up into two streams by the vertical ducts 26 which carry the air downwardly and into the front ends

20 of horizontal ducts 27 which open through the rear of the car and discharge into the atmosphere. In the lower part of the ducts 26 are electric or other suitable fans 28 which aid in the discharge

25 of the air and measurably reduce the resistance to the passage of the air by the ducts produced by the tortuous character of the ducts, so that the resistance to forward motion of the car is reduced to a minimum while the mail receiving

30 opening 15 is open by reason of the open position of the doors 16 and 17. Another important function of the ducts 26, 27 and the fans 28 is to reduce the effect of the vacuum behind the car when the car is travelling at high speed, thereby

35 preventing a car following motion of the mail bags when dropped from the rear of the car, doors 16 and 17 being open for mail or partly open for air supply.

The rearmost wall of the car is composed of a tail gate 29 which ordinarily closes the rear mail discharging opening 30, the said gate being

40 hinged as indicated by the numeral 31 and arranged to be supported in horizontal position while open by a chain 32 and to be held closed in a closed position by the latch arrangement 33.

45 The axle 34 of the forward wheels of the rear truck has thereon a belt pulley 35 over which is trained a belt 36 which leads upwardly through the floor of the car and through a protecting casing 37 and over a pulley 38 on the clutch shaft

50 39 which is rotatably supported by a bracket 40, as shown in Figure 5, the said clutch shaft having on the opposite side of the bracket 40 and rotatable relative to the shaft 39 the small gear 41 and the larger gear 42 which are held properly

55 spaced by positioning collars 43 and 44. Between these gears is the slidable clutch member 45 which is splined to the shaft 39 and movable selectively

60 into operative engagement with the gear 41 or with the gear 42 by the clutch fingers 46 and 47 which are operatively connected to the clutch

65 lever 48 which is pivoted as indicated at 49 and which extends downwardly through the ceiling portion 19' and through a flexible retainer 50 to an operative position within the compartment 19

70 just forward of the wall 51 which encloses the rear of the conveyor compartment 20, the said wall having a conveyor inspection window 52 and an elephant-trunk chute 53 which has its upper

75 forwardly tending end which is in communication with the compartment 20 and slightly tapers downwardly and toward the right side wall of the car and opens forwardly so as to deliver the sacks or bags of mail onto the floor within the chute 53 of the elevated part 8 in the compartment 19 for manual handling by the railroad

crew to the mail crew in the sorting and packing postal compartment forward of the compartment 19.

5 Mounted in suitable brackets on the ceiling 19' and within the conveyor compartment 20 is the shaft 55 which has fixed thereto the relatively large gear 56 with which the clutch shaft gear 41 is constantly meshed and the relatively small gear 57, with which the clutch shaft gear 42 is constantly meshed. When the clutch operating lever 48 is manipulated so as to bring the clutch member 45 having automobile type clutch ends engageable with a similar end on each of the gears 41 and 42, into engagement with the gear 41 the conveyor belts to be described are driven at a relatively low speed; while when the clutch member 45 is disengaged from the gear 41 and engaged with the gear 42 the shaft 55 and hence the said conveyor belts will be driven at a relatively high rate of speed.

20 Forwardly of the shaft 55 is another shaft 58 and over the shafts 55 and 58 is trained a smooth conveyor belt 59 which travels at a relatively slow speed. Above the shaft 58 is supported another shaft 60 which is sprocket driven from the shaft 58 to drive the cleat equipped conveyor belt 61 at a higher speed than the belt 59 the belt 61 being trained over the shaft 60 and over another forwardly located shaft 62 which is, in turn, in sprocket drive relation to another shaft 63 which has trained thereover the cleat equipped conveyor belt 64 which is, in turn, trained over the shaft 65 which is forward of the shaft 63. The shaft 65 sprocket drives another shaft 66 which has trained thereover the cleat equipped conveyor belt 67 which is, in turn, trained over the shaft 68 forwardly of the shaft 66. The shaft 68 sprocket drives the shaft 69 which has trained thereover the higher speed conveyor belt 70 which is, in turn, trained over the shaft 71 close to the front end of the car and immediately within the opening 15. When the doors 16 and 17 are in their open positions the high speed conveyor 70 is exposed or uncovered to receive the mailbags or sacks from the stationary rack at the station or other location.

40 The arrangement of the sprocket drives between the various conveyor belts is such that the high speed conveyor belt 70 is traveling toward the rear at a speed substantially that of the forward motion of the car, so that the mailbags or sacks upon contact with the belt 70 are carried toward the conveyor belt 67 at a rate which prevents impact and tearing of the bags such as ordinarily occurs when semi-rigidly mounted hooks or the like are applied to the bags on a stationary station rack in taking the bags from the rack. The second conveyor belt 67 is moving rearwardly at a speed less than that of the first belt 70, the belt 64 is moving at a speed less than that of the belt 67, and the belt 61 is moving at a rate of speed less than that of the belt 64, while the belt 59 is moving at a relatively slow rate; so that the mail sacks are carried rearwardly first at a rate approximating that of the forward travel of the car and then at a gradually reduced rate until the mail is finally delivered to the chute 53 at a very slow rate so that the mail will slide through the chute and on to the floor of the compartment 19 at a desirable slow rate.

45 However, the conveyor belts can be driven from the shaft 39 at either one of two different speeds through means of gears 41 and 42 and the clutch member 45. This enables the rate of travel of

mail bags over the conveyor means to be regulated to a certain extent.

It is to be observed that the handling compartments below the ceiling 19' will preferably be low but the floor 11 is low set on account of the low-slung arrangement of the car frame or chassis, so that generally speaking ample headroom obtains throughout the car enabling the crews to work in standing positions. The numerals 11' and 72 indicate doors in the side wall of the car.

The means for handling the mail in the car while the car is traveling at relatively high speeds, say from 70 to 90 miles per hour, have been described above. I will now describe the means whereby the mail may be discharged onto the tracks or ground without jarring or injury to the sacks or their contents and while the car is traveling at equally high speeds. The mechanism comprises the centralized longitudinal air pressure cylinder 73 which has therein the piston 74 having the connecting rod 75 extending through the rear of the cylinder and connected to the L-shaped platform 76 which is preferably composed of L-shaped bars and may be rollably supported on rollers or the like 77 placed rearwardly, so as to be capable of being extended through the rear opening 30 and out over and behind the tail gate 29 as shown in Figure 7.

The pressure cylinder 73 has a low pressure connection 78 and which is sufficient to move the piston 74 rearwardly in a relatively slow manner so as to start the platform rearwardly after the gate 29 has been manually opened, the platform containing the sacks of mail to be dropped from the car. Spaced from the front end of the cylinder 73 is the conduit 79 which leads from a high pressure cylinder 80 which has a high pressure connection 81. The conduit 79 is not uncovered by the piston 74 of the cylinder 73 until the platform 76 has been worked rearwardly well on its way. As soon as the piston 74 in its rearward travel uncovers the conduit 79, the platform 76 will be shot rearwardly at sufficiently high speed to deposit the mail sacks on the ground or tracks without appreciable momentum, so that the sacks will not hit the ground heavily and the contents of the sacks will not be jarred, as would be the case if the sacks were simply dropped off the back end of the car.

For holding the platform 76 in retracted position as shown in Figure 9, I provide the latch arrangement which is generally designated 82 and which comprises the bracket 83 fastened to the floor of the compartment 19, the shaft 83 mounted in said bracket and having the L-shaped arms 84 and 85 at its opposite ends which include the rollers 86 and 87 which engage the depending flange of the angle iron form 88 at the rearward side thereof to hold the platform 76 in retracted position. Sufficient clearance is provided between the lower edge of the angle iron 88 and the floor of the compartment. When the lever 89 is pulled forwardly, the rollers 86 and 87 are moved upwardly along the member 88 until the member 88 clears the rollers by an upward swing of the arms 84 and 85, the platform 76 is free to be pushed rearwardly by operation of the cylinder 73 into the fully extended position shown in Figure 7. Suitable means may be provided for retracting the platform 76 into the initial position shown in Figure 9, or the same may be manually retracted.

Although I have shown and described herein a preferred embodiment of my invention, it is to be definitely understood that I do not desire to

limit the application of the invention thereto, and any change or changes may be made in the materials, and in the structure and arrangement of the parts, within the spirit of the invention and the scope of the subjoined claims.

What is claimed is:—

1. A railway mail motor car comprising a wheeled body formed in its front end with a mail receiving opening, a rearwardly moving conveyor arrangement extending into said opening and designed to receive a sack of mail coming through said opening, said conveyor arrangement comprising a plurality of flights and means for driving each succeeding flight at a lower rate of speed than the preceding one, said means including means for driving the front portion of said conveyor arrangement at a speed approximately the speed of forward movement of the car.

2. A railway mail car comprising a wheeled body formed in its front end with a mail receiving opening, a rearwardly moving conveyor arrangement extending into said opening and designed to receive a sack of mail coming through said opening, and means driving a front portion of said conveyor arrangement at a speed approximately the speed of forward movement of the car, so as to avoid impacting the sack of mail, said car including means receiving the sack of mail from the rear end of the conveyor arrangement, said conveyor arrangement comprising rearwardly succeeding flights, each succeeding flight moving at a slower rate of speed than the preceding flight.

3. A railway mail car comprising a wheeled body formed in its front end with a mail receiving opening, a rearwardly moving conveyor arrangement extending into said opening and designed to receive a sack of mail coming through said opening, and means driving a front portion of said conveyor arrangement at a speed approximately the speed of forward movement of the car, so as to avoid impacting the sack of mail, said car including means receiving the sack of mail from the rear end of the conveyor arrangement, said conveyor arrangement comprising rearwardly succeeding flights, each succeeding flight moving at a slower rate of speed than the preceding flight, said flights being operatively connected, and the rear flight being driven from a track or ground engaging wheel, whereby said flights are operated at speeds coordinated with respect to the speed of forward motion of the car.

4. A railway mail car comprising a wheeled body formed in its front end with a mail receiving opening, a rearwardly moving conveyor arrangement extending into said opening and designed to receive a sack of mail coming through said opening, and means driving a front portion of said conveyor arrangement at a speed approximately the speed of forward movement of the car, so as to avoid impacting the sack of mail, said car including means receiving the sack of mail from the rear end of the conveyor arrangement, said conveyor arrangement comprising rearwardly succeeding flights, each succeeding flight moving at a slower rate of speed than the preceding flight, said flights being operatively connected, means for driving the rear flight from a track or ground engaging wheel, whereby said flights are operated at speeds coordinated with respect to the speed of forward motion of the car, and said drive means for the rear flight including selective speed transmission means whereby the speed of

the rear flight may be reduced or increased to predetermined extents.

5. A railway mail car of the character described, said car including a body having a floor and also having track engaging wheels, the forward end of said body being formed with a mail sack receiving opening, rearwardly moving conveyor means extending into said mail sack receiving opening for conveying a received sack of

10 mail rearwardly in said body, said conveying means being located above said floor and a substantially spiral chute in the body receiving the sack from the conveying means and conveying it downwardly to the floor of the body.

15 6. A railway mail car of the character described comprising an elongated body having a mail sack receiving opening in its front end, a compartment in the upper part of the body, means in the compartment for rearward transfer of the 20 mail received through said opening, said compartment having a direct connection with said opening, and air ducts leading from the rear of said compartment and extending at opposite sides of the rear portion of the body and opening 25 through the rear end of the body, said air ducts being arranged to relieve the rearwardly rushing air pressure in said compartment caused by high speed forward movement of the car.

7. A railway mail car of the character described comprising an elongated body having a mail sack receiving opening in its front end, a compartment in the upper part of the body, means in the compartment for rearward transfer of the mail received through said opening, said 30 compartment having a direct connection with

said opening, and air ducts leading from the rear of said compartment and extending at opposite sides of the rear portion of the body and opening through the rear end of the body, said air ducts being arranged to relieve the rearwardly rushing air pressure in said compartment caused by high speed forward movement of the car, and doors on the front of the body for closing the mail sack receiving opening.

8. A railway mail car of the class described, 10 comprising an elongated body having an opening at one end for the passage of a mail sack, and sack conveying means in the body and having an end arranged adjacent the opening and door means for closing the opening.

15 9. A railway mail car of the class described, comprising an elongated body having a discharge opening at its rear end, conveyor means in the body for discharging a sack of mail through the opening, an opening in the front end of the body, 20 a passage extending longitudinally in the body and having one end in communication with the front opening, and air ducts leading from the rear end of said passage and extending at opposite sides to the rear portion of the body and 25 opening through the rear end of the body at the sides of the rear opening, said ducts being arranged to relieve the low pressure area immediately adjacent the rear end of the car by delivering to such area the rearwardly rushing air 30 which flows through the passage and ducts when the train is moving forwardly at high speed, thus preventing the mail bag deposited on the track from following the car.

SAMUEL E. WILEY. 35
